IMPACT WRENCH

R Stanford Short, Bryan, Ohio, assignor to The Aro Equipment Corporation, Bryan, Ohio, a corporation of Ohio

Application December 31, 1956, Serial No. 631,751

13 Claims. (Cl. 192—30.5)

This invention relates to an impact wrench or similar type of impacting tool wherein rotary impact blows are delivered by an output end of the mechanism when a pneumatic motor or the like is connected with the input end thereof and energized for rotating the mechanism.

One object of the invention is to provide a comparatively simple and rugged mechanism interposed between a source of power and the work, such as screwing a nut on a bolt, for initially rapidly rotating the work until a predetermined resistance to torque has been built up whereupon the mechanism operates to deliver a series of rotary impact blows to the work as long as the motor continues to operate. Conversely, as when loosening a nut, impact blows are first delivered until the nut is loose and then it is automatically quickly rotated off the bolt when the resistance to torque reduces because of the nut being loosened.

The prime object of the invention is to provide a design in which multiple motor revolutions are permitted per impact blow and thus a harder impact blow is produced by increasing the momentum of the mechanism.

Another object is to provide a mechanism of inexpensive construction involving a minimum number of parts, and so designed as to require a minimum of time and parts in replacement when the wear advances to a stage requiring such replacement.

Another important object of the invention is to provide an impacting mechanism having a power-driven member and an anvil, with a hammer interposed between the two and so related thereto as to be clutched and declutched relative to the power-driven member and also relative to the anvil, the operation being such that the hammer is sequentially rotated by the power-driven mechanism, then released therefrom, then clutched in relation to the anvil for delivering an impact blow thereto and finally released from the anvil and re-engaged with the power-driven member during a complete cycle of impacting operation, thus permitting the hammer member to rotate as a free body prior to delivering the impact blow.

Still another object is to provide an impact clutch construction in which an impacting element and hammer driving elements of the clutch are mounted within a hammer element for axial movement relative thereto and independently thereof to permit clutching and declutching in relation to an anvil and in relation to a power-driven member respectively whereby rotary impact momentum of all the elements together is imparted to the anvil upon impact. Such hammer, impacting and driving elements are proportioned to provide a relatively rugged mechanism conducive to less wear than the usual type of impact clutch by positive disengagement of the impact element from the anvil face following impact. Thus, disengagement and relative sliding motion between the impact element and the anvil face are permitted after the impact is dissipated to the work and the engaging surfaces are at minimum unit pressure as distinguished from other impacting mechanisms which declutch during the impact

2

and therefore during a time when high unit pressures are involved. I also provide extensive supporting and bearing surfaces for the impact and hammer driving elements throughout the major portions of their lengths which further contributes to minimizing wear, and whereby the radial dimensions of the clutch are brought within relatively small limits for ease in handling and manipulation of the tool.

A further object is to provide a mechanism wherein 10 the hammer is released from the motor prior to impact so that the hammer and impacting member carried thereby strike a blow on the anvil as a free body, thereby eliminating the effects of the blow being carried back through the mechanism and imparted to the motor which results 15 in improving motor and bearing life and improving motor performance and efficiency.

Still a further object is to provide a positive means of 20 clutching and declutching the hammer with respect to the anvil controlled by the motor rotation and in controlled time relationship with the anvil, thereby controlling the number of revolutions per impact blow.

An additional object is to provide impacting mechanism 25 in which the hammer member is released from the power-driven member to allow the motor driving the power-driven member to recover speed before the hammer is re-engaged therewith, thereby permitting more rapid acceleration of the hammer upon re-engagement.

Another additional object is to provide impacting mechanism 30 designed so that eccentricities of rotating members are minimized or eliminated, thereby reducing or eliminating shaking forces or vibration being set up in the mechanism which are uncomfortable to and/or uncontrollable by the operator and in which wear is minimized by the impacting member and the hammer driving members 35 are rotated to present a different striking surface each time.

A further additional object is to provide an impact 40 clutch construction wherein the impacting element is in the form of a rod extendable through the end portion of the hammer member and opposed to the anvil member to engage and impart hammer blows on the anvil member in the movement of the rod axially relative to the hammer and dependent on the position of the power-driven member.

Still a further additional object is to provide an impact 45 clutch construction wherein the hammer driving element is in the form of a rod which extends from an end of the hammer member and engages or releases the hammer in respect to the motor driven member by means of axial 50 movement of the rod relative to the hammer and independently thereof, such movement being dependent on the position of the anvil member.

Constructionally, I provide rotatable power-driven hammer and anvil members with pin-like hammer driving and 55 impacting members slidable axially in the hammer member and controlled by cams on the anvil and power-driven member respectively, the hammer driving members being clutched and de-clutched relative to the power-driven member by the cam of the anvil and the impacting member being clutched and declutched relative to the anvil by a cam groove of the power-driven member.

With these and other objects in view, my invention consists in the construction, arrangement and combination of the various parts of my impact wrench, whereby the objects above contemplated are attained, as hereinafter more fully set forth, pointed out in my claims and illustrated in detail on the accompanying drawings, wherein:

Fig. 1 is a vertical sectional view through an impact wrench embodying my present invention and showing 70 the adjacent portion of a pneumatic motor on which it is mounted;

Figs. 2 and 3 are vertical sectional views on the lines

2-2 and 3-3 respectively of Fig. 1, the impact wrench of Fig. 1 being taken on the line 1-1 of Fig. 2;

Fig. 4 is an exploded perspective view of the impacting mechanism, the housing therefor and the adapter for mounting the housing on a pneumatic motor, the parts of a hammer assembly thereof being in assembled relation;

Fig. 5 is a further exploded perspective view of the hammer assembly portion of Fig. 4;

Fig. 6 is a series of four cross-sections, two somewhat like Fig. 1 and two like Figs. 2 and 3, and each of the four identified by legend and section lines as to where the cross-sections are taken, the four sections showing the relative positions of parts of the impact mechanism at the time of impact;

The legends and section lines also apply to Figs. 7, 8, 9 and 10 which are similar sectional views showing further positions of the parts during other portions of one complete impacting cycle;

Fig. 11 is a developed sectional view of a cam groove for an impacting member and is formed in the periphery of a power-driven member of the impacting mechanism as taken on the line 11-11 of Fig. 2; and

Fig. 12 is a similar developed sectional view of a cam surface for a hammer driving member, this cam surface being formed on an anvil as indicated by the line 12-12 of Fig. 3.

On the accompanying drawings I have used certain reference letters to indicate in general the main parts of my impact mechanism and a list thereof follows:

- P—power-driven member
- H—hammer
- A—anvil
- I—impacting member
- D¹—hammer driving member
- D²—hammer driving member

There is also provided a housing 10 for the foregoing parts. It has a flange 12 secured to an adapter 16 by cap screws 14 (see Figs. 1 and 4) and the adapter is mounted on a pneumatic motor housing or the like 18. The stator of this motor is indicated at 20 and the rotor thereof at 22, a vane type motor being illustrated and the vanes being indicated at 24. The rotor 22 has a shaft 26 which is splined as indicated at 28 to interfit with a splined bore 30 of the power-driven member P.

The hammer H has a central bore 32 which receives a bushing 34 for journaling the hammer H on the power-driven member P. The member P is supported at its right-hand end in Fig. 1 on the rotor shaft 26 and at its left-hand end on a ball spacer 36 seated between this left-hand end and the anvil A. The ball 36 transmits thrust of the anvil A during operation of the tool through the member P to a ball bearing of the pneumatic motor. The anvil A has a shaft-like portion 38 journalled in a bushing 40 of a hub 41 on the housing 10. A grease seal is provided at 39. Thrust surfaces 42 of the anvil and 44 of the bushing are shown in engagement with each other. The shaft-like portion 38 terminates in a squared portion 46 to engage in a wrench socket or other tool to which rotary impact blows are to be imparted.

The hammer H also has a bore 48 to slidably and rotatably receive the impacting member I, and a pair of bores 50 to slidably and rotatably receive the hammer driving members D¹ and D².

The power-driven member P has a projection 53 provided with drive shoulders 52 and 54 for coaction with the hammer driving members D¹ and D². The shoulder 52 is for clockwise rotation and the shoulder 54 is for counterclockwise rotation. It also has a cam groove 56 that receives a flange 58 of the impacting member I for axially sliding this member in its bore 48 as will hereinafter appear.

The anvil A has a projection 61 provided with an impact receiving shoulder 60 for cooperation with the im-

pacting member I when the impact mechanism rotates counterclockwise. It also has a cam surface 64 to actuate the hammer driving members D¹ and D² by cooperation with heads 66 thereof. The cam surface 64 as shown in Fig. 12 is depressed relative to a land 65 of the anvil A. The heads 66 cooperate with the land 65 also so that 64 and 65 together are the controlling cam surface for the hammer driving members during 360° of rotation.

The hammer driving members D¹ and D², as shown in Fig. 1, each comprises a sleeve 68 in which a stem 70 of the head 66 is slidably mounted and limited in its sliding movement by opposed slots 72 of the sleeve and a pin 74 extending through the stem 70 and having its ends located in the slots 72. A cam follower spring 76 is provided under the head 66 to cause it to follow the cam surface 64-65 against the hammer H. A hammer driving member extension spring 78 is provided under the head 66 and seats against the end of the sleeve 68 to normally retain the pins 74 at the left end of the slots 72 and thus the sleeve 68 and the stem 70 extended relative to each other, yet permit their contraction in length as permitted by the pin and slot connection in case the driving members D¹ and D² strike the under face (left-hand face in Figs. 1 and 4) of the projection 53.

Practical operation

Various positions of the parts during an impacting cycle are illustrated in Figs. 6 to 10 inclusive. These figures are somewhat diagrammatic and the hammer driving members D¹ and D² are shown of simple one-piece construction instead of the telescoping sleeve and stem type illustrated in Fig. 1 as the telescoping construction does not enter into the impacting operation except to prevent breakage of the parts in the event that the member D¹ or D² is driven by the cam surface 64 against the projection 53 when it is in a position of registry with respect to either D¹ or D². The telescoping connection permits the stem 70 to slide into the sleeve 68 opposed by the spring 78 until the projection 53 has moved out of the way whereupon the spring 78 will expand for again telescoping the member D¹ or D² to its original length.

When a suitable socket or adapter (not shown) is associated with the squared portion 46 of the anvil A and such socket is applied to a nut, cap screw or the like for tightening it (clockwise rotation), the parts would be in the position of Fig. 6 at the instant of impact. The impacting member I is positioned axially by the cam groove 56 to engage with the impact receiving shoulder 62 of the projection 61 of the anvil A as shown in sec. F-F. Hammer driving member D² is shown in a retracted position with respect to the projection 53 as permitted by the cam surface 64 and as caused by the spring 76 as shown in sec. A-B-D. This retraction of the driving member D² is accomplished several degrees of rotation prior to the position of Fig. 6, thus disengaging the power-driven member P from the driving member D² which releases the hammer H. This permits the hammer to rotate momentarily as a free body until the impact member I that it carries delivers an impact blow to the impact receiving shoulder 62 of the anvil A. The driving member D¹ is in an engaging position as shown in sec. A-B-C.

The power-driven member P having been disengaged in Fig. 6 is free to rotate relative to the hammer H to the position shown in Fig. 7 (sec. E-E). This relative rotation permits the cam groove 56 to declutch the hammer H from the anvil A by retracting the impacting member I (secs. A-B-C and A-B-D). The position of all members except P and I remain the same as in Fig. 6.

In Fig. 8, the power-driven member P continues to rotate relative to the hammer H until the driving member D¹ is engaged by the drive shoulder 52 as shown in sec. E-E. The cam groove 56 continues to hold the impacting member I retracted or disengaged relative to the anvil. During this rotation all members except the power-

driven member P remain in the same position as shown in Fig. 7.

The free rotation of the anvil A prior to impact may be achieved with the parts positioned as shown in either Fig. 8 or Fig. 10. Assuming the parts in the position of Fig. 8, the shoulder 52 of the projection 53 of the power-driven member P must engage D¹. Driving member D² must be positioned in cam 64 of anvil A. The camming action of the head 66 on 64 is opposed by the spring 76 and driving of the anvil A is achieved. When a resistance to torque is encountered by the anvil A, this spring 76 yields to the camming action between 66 and 64 and the impact cycle begins. Free rotation of the anvil A can be achieved similarly with the parts positioned as shown in Fig. 10 but D² in that case must be driven by shoulder 52, and D¹ must be positioned in cam 64 as previously described for D¹ in connection with Fig. 8.

It is also possible to drive the anvil in free rotation prior to impact with the parts in a position intermediate Figs. 6 and 7. In this position, D¹ and D² would be as shown in Fig. 6 and P would be rotated approximately 60° clockwise of Fig. 6, sec. E—E. With the parts so arranged the impact element I would be engaged with the anvil A on shoulder 62. Its head 58 would be driven by the cam 56 of P until torsional resistance to A is encountered. This resistance would then resist I independently of P and thus permit the normal camming action of I and P to cause P to rotate to the position of Fig. 7 and start the impacting cycle.

Assuming the impacting mechanism to have been freely rotating the anvil A from the position of Fig. 10, when resistance to anvil A is encountered D¹ is cammed relative to anvil A to permit rotation of the hammer H relative to the anvil A through approximately 240° to the position shown in Fig. 6.

Referring to Fig. 9, the driver D² is cammed into an engaging position due to the rotation of the hammer H relative to the anvil A. The driver D¹ is cammed out of the engaging position just prior to the position of Fig. 9.

Between the positions shown in Fig. 9 and Fig. 10, the impact element I is cammed by the action of 56 on 58 into a position to engage A. When P engages D², the action continues as in Fig. 10. As the motor continues to rotate beyond the position shown in Fig. 10, the hammer H is rotated relative to the anvil A until the position shown in Fig. 6 is again reached at which time the impacting cycle has been completed and the next impact blow thereupon occurs.

The sequence of operations described achieves one impact blow per two revolutions of the motor, the first revolution being utilized primarily for clutching and de-clutching actions and the second revolution being employed primarily to accelerate the hammer. The hammer is then picked up again by the power-driven member and rotated for delivering the next impact blow but is released from the power-driven member before the blow is struck. The hammer carries the impacting member and causes it to strike a blow on the anvil while the hammer and impact members are revolving as a free body thereby eliminating the effects of the impact being transmitted directly to the motor and thereby improves the life of the motor. This constructional and operational arrangement accomplishes the objects set forth at the beginning of my specification and does so with a mechanism that has relatively few operating parts. By incorporating additional hammer driving members such as D¹ and D², the number of revolutions per impact blow can be increased.

Some changes may be made in the construction and arrangement of the parts of my impact wrench without departing from the real spirit and purpose of my invention, and it is my intention to cover by my claims any modified forms of structure or use of mechanical equivalents which may reasonably be included within their scope.

I claim as my invention:

1. In a rotary impact tool, an impact mechanism comprising an input element, an output element and a hammer element, said hammer element being adapted to be driven by said input element whereby to rotate said output element, and at times to impart impact blows thereto, a first means for clutching and declutching said hammer element relative to said input element, a separate second means for clutching and declutching said hammer element relative to said output element, said first means having a direct camming connection with said output element and thereby being responsive to relative motion between said hammer element and said output element, said second means having a direct camming connection with said input element and thereby being responsive to relative motion between said hammer element and said input element, and the clutching and declutching action being responsive to resistance to torque.

2. In a rotary impact tool, an impact mechanism comprising a power-driven element, an anvil element, a hammer element to be driven by said power-driven element and to rotate said anvil element and deliver impact blows thereto, means for clutching said hammer element relative to said power-driven element and declutching it relative to said anvil element to transmit rotation from said power-driven element to said hammer element, and means responsive to resistance to torque for declutching said hammer element from said power-driven element and clutching it to said anvil element to deliver a rotational impact blow thereto, said means comprising a hammer driving element which is cam operated from said anvil element and an anvil engaging element which is cam driven from said power-driven element.

3. In a rotary impact tool, an impact mechanism comprising an input element, an output element and a hammer element, said hammer element having a first element movably carried thereby to be driven by said input element and a second element movably carried by said hammer element to rotate therewith and to impart impact blows to said output element upon predetermined resistance to torque, means for clutching and declutching said first element relative to said input element, first and second means for clutching and declutching said second element relative to said output element, said first means being responsive to relative motion between said hammer element and said output element and said second means being responsive to relative motion between said hammer element and said input element.

4. In a rotary impact tool, an impact mechanism comprising an input element, an output element and a hammer element, said hammer element having a first movable element to be driven by said input element and having a second movable element to rotate said output element and impart impact blows thereto upon predetermined resistance to torque, first and second means for clutching and declutching said movable elements relative to said input element and relative to said output element, said first means being cam responsive, and said output and input elements having cams for actuating said means in response to resistance to torque.

5. In a rotary impact tool, an impact mechanism comprising an input element, an output element, and an operative connection between the two comprising solely a hammer element and first and second declutching means carried by said hammer element, said hammer element being provided to be driven by said input element through said first declutching means only and to drive said output element and deliver impact blows thereto through said second declutching means only, said first means only clutching said hammer element relative to said input element to transmit rotation from said input element to said hammer element and declutching said hammer element relative to said input element to permit said hammer element to rotate as a free body, said second means only clutching said hammer element rela-

tive to said output element for normally rotating said output element and for delivering impact blows thereto upon predetermined resistance to torque being encountered and declutching said hammer element relative to said output element to permit reclutching of said hammer element relative to said input element by said first means only.

6. In a rotary impact tool, an impact mechanism comprising a power-driven element, an anvil element, a hammer element to be driven by said power-driven element and to rotate said anvil element and deliver impact blows thereto, means for clutching said hammer element relative to said power-driven element and declutching it relative to said anvil element to transmit rotation from said power-driven element to said hammer element, means responsive to resistance to torque for declutching said hammer element from said power-driven element and clutching it to said anvil element to deliver a rotational impact blow thereto, said means comprising a hammer driving element, a cam on said anvil element for actuating said hammer driving element, an impacting element, a cam on said power-driven element for actuating said impacting element, and said hammer driving and impacting elements being carried by said hammer element and movable relative thereto under the action of said respective cams.

7. In a rotary impact tool, an impact mechanism comprising an input element, an output element and a hammer element located axially between said input element and said output element, said hammer element being adapted to be driven by said input element whereby to rotate said output element, and at times to impart impact blows thereto, a first means axially slidable of said hammer element for clutching and declutching said hammer element relative to said input element, and separate second means axially slidable of said hammer element for clutching and declutching said hammer element relative to said output element, said first means having a projection and said output element having a cam coacting therewith to effect axial sliding of said first means relative to said hammer element, said second means having a projection and said input element having a cam coacting therewith to effect axial sliding of said second means relative to said hammer element.

8. In a rotary impact tool, an impact mechanism comprising an input element, an output element and a hammer element, said hammer element having an axially slidible element to be driven by said input element and an axially slidible element to rotate said output element, and to impart impact blows thereto upon predetermined resistance to torque, means for clutching and declutching said first slidible elements relative to said input element, means for clutching and declutching said second slidible element relative to said output element, said first means being responsive to relative motion between said hammer element and said output element and said second means being responsive to relative motion between said hammer element and said input element, said first slidible element being of spring extended, telescopic construction.

9. In a rotary impact tool, an impact mechanism comprising an input element, an output element and a hammer element, said hammer element having a first slidible element to be driven by said input element and having a second slidible element to rotate said output element and impart impact blows thereto upon predetermined resistance to torque, means for clutching and declutching said slidible elements relative to said input element and relative to said output element, said means being cam responsive, said output and input elements having cams for actuating said means, said first slidible element being of telescopic character, spring means to normally extend the same, and means to limit such extension.

10. In a rotary impact tool, an impact mechanism comprising a power-driven element, an anvil element, a hammer element to be driven by said power-driven ele-

ment and to deliver impact blows to said anvil element, first means for clutching said hammer element relative to said power-driven element and declutching it relative to said anvil element to transmit rotation from said power-driven element to said hammer element, and separate second means responsive to resistance to torque for declutching said hammer element from said power-driven element and clutching it to said anvil element to deliver a rotational impact blow thereto, said first means being carried by said hammer element and being movable into and out of the path of said power-driven element only and said second means being carried by said hammer element and being movable into and out of the path of said anvil element only.

15. In a rotary impact tool, an impact mechanism comprising a power-driven element, an anvil element, a hammer element to be driven by said power-driven element and to deliver impact blows to said anvil element, first means for clutching said hammer element relative to said power-driven element and declutching it relative to said anvil element to transmit rotation from said power-driven element to said hammer element, and second means responsive to resistance to torque for declutching said hammer element from said power-driven element and clutching it to said anvil element to deliver a rotational impact blow thereto, said first means being carried by said hammer element and being movable into and out of the path of said power-driven element and said second means being carried by said hammer element and being movable into and out of the path of said anvil element and cams on said anvil and power-driven elements for actuating said first and second means respectively.

20. In a rotary impact tool, an impact mechanism comprising an input element, an output element and a hammer element, said hammer element having a first movable element to be driven by said input element and having a second movable element to rotate said output element and impart impact blows thereto upon predetermined resistance to torque, first and second means for clutching and declutching said movable elements relative to said input element and relative to said output element, said second means being cam responsive, and said output and input elements having cams for actuating said means in response to resistance to torque.

25. In a rotary impact tool, an impact mechanism comprising an input element, an output element, and an operative connection between the two comprising solely a hammer element and first, second and third declutching means carried by said hammer element, said hammer element being provided to be driven by said input element through said first declutching means only in one direction and said second declutching means only in the opposite direction, and to drive said output element and deliver impact blows thereto through said third declutching means only, said first or second means only clutching said hammer element relative to said input element to transmit rotation from said input element to said hammer element and for declutching said hammer element relative to said input element to permit said hammer element to rotate as a free body, said third means only clutching said hammer element relative to said output element for normally rotating said output element and for delivering impact blows thereto upon predetermined resistance to torque being encountered, and declutching said hammer element relative to said output element to permit reclutching of said hammer element relative to said input element by said first or second means only depending upon the direction of rotation.
